4 Claims. (Cl. 315—39.63)

This invention relates to multi-cavity magnetron oscillators and amplifiers of the injection type and has for its object to provide an improved electrode arrangement for such devices.

Magnetrons are known in which an annular beam of electrons is injected from one end of, and into an annular interaction space between a cavity anode and an electrode coaxial therewith and maintained at a negative potential with respect to the anode. In such known types of magnetron, however, the electrons in the beam enter the interaction space with widely varying angular velocities, resulting, in part, from the dispersion of the electron emitting surface with relation to the remaining electrodes.

It is a further object of the invention to provide improved means for injecting the electron beam so that all or a majority of, the electrons in the beam have almost a uniform angular velocity on injection.

A magnetron in accordance with the invention has an electrode system arranged to produce, in an annular space, a wall of which is formed to provide resonant cavities, a radial electrostatic field, into one end of which space a cylindrical beam of electrons is injected, the electrons injected into said space being caused to proceed in substantially helical paths by means of an axial magnetic field produced therein whereby to induce or amplify oscillations in said cavities.

In carrying out the invention a short cylindrical cathode, preferably of the emission-limited type, is mounted at one end of the magnetron co-axial with the annular space in which a radial electric field is developed, the cathode being surrounded by an annular anode concentrically disposed and at a positive potential with respect to the cathode. Electrons are emitted by the cylindrical surface of the cathode when it is heated, and travel towards the annular anode, but they are deflected in an axial direction by an annular electrode at negative potential, situated adjacent the annular gap between the cathode and the annular anode.

Partly shaded from the cathode by the annular anode is a main anode which forms a wall of the annular space. The main anode is of larger diameter than the annular anode, has the resonant cavities formed therein, and is mounted co-axial with the annular anode. The main anode is axially displaced with respect to the annular anode and is at a more positive potential. Concentrically within it is located a cylindrical electrode at a negative potential with respect to the main anode and to the cathode. There is thus developed in the annular interaction space between the main anode and the cylindrical electrode within it an electric field into which the annular beam of electrons originating at the cathode is injected.

2

The invention will be more readily understood from a consideration of the following description of an embodiment shown in the accompanying drawings, in which

Fig. 1 is a diagrammatic representation of the electrode structure of the magnetron indicating the electron paths,

Fig. 2 is a plan view of the magnetron, partly broken away, and

Fig. 3 is a cross-section on the line 3,3, of Fig. 2.

Referring to Fig. 1, the main cavity anode is shown at 10; concentrically located within it and shown in interrupted lines is a cylindrical post electrode 11, maintained at a negative potential with respect to the main anode and to the cathode 12. The cathode 12 and its associated electrodes are designed to inject into the annular interaction space between the main anode 10 and the cylindrical electrode 11 a hollow cylindrical beam of electrons, indicated at 13. The electron beam, as well as being projected axially into the annular space between the main anode 10 and the cylindrical electrode 11, is influenced by a magnetic field produced axially of the electrode structure (not shown) as indicated by the arrowed lines, so that the electrons are given a continuous circumferential component of motion resulting in the electrons in the beam proceeding in a helical path, indicated at 14. The annular beam of electrons is produced by forming the cathode 12 with an annular emissive surface 15 from which the electrons emerge, the electrons being emitted initially in a radial direction by the electrostatic field produced between the cathode 12 and a first annular anode 16, shown in interrupted lines, and maintained at a positive potential with respect to the cathode. The annular beam of electrons is injected into the annular interaction space by means of an annular deflecting electrode 17 maintained at a high negative potential with respect to the cathode. The arrangement of the electrodes and the potentials applied to them are such that the electrons in the annular beam are rotating in a helical path when they enter the interaction space with an angular velocity synchronous with the wave which propagates on the anode circuit.

The spatial arrangement of the electrodes is shown more clearly in the cross-section of the magnetron illustrated in Fig. 3, in which similar reference numerals have been used to indicate corresponding parts referred to in connection with Fig. 1.

The cathode 12 is preferably of the emission-limited type; i. e. emission is temperature limited, i. e. it is determined by the temperature and not by the space charge, and may consist, for instance, of a disc of tantalum. It is heated by radiation from a filament 18 to which heating current is applied through a lead-in conductor 19, the other end of the heating filament being connected to the stem 20 which supports the cathode disc.

The stem 20 is secured to cover plate 21 which, together with cover plate 22 and the annular wall 23, constitute the evacuated envelope of the magnetron. The heating filament 18 is surrounded by a shield 24 which confines the radiation from the filament and directs it upon the adjacent surface of the cathode disc 12. The heat shield 24 is maintained at a negative potential with respect to the cathode and its dependent rim serves as the negative electrode 17 of Fig. 1, which causes the electron beam to be injected into the annular interaction space. The shield 24 is supported from the cathode stem

20 by means of an insulating collar 25, and is connected electrically to an insulated bushing 32.

Coaxial with the cathode is mounted the cylindrical electrode 26 between which and the anode 10 is formed the annular interaction space into which the electron beam is injected. Electrode 26 is mounted upon a stem 27 insulatingly supported from the cover plate 22. Electrode 26 is in the form of a hollow cylinder having a central web 28 by which it is mounted upon the stem 27, the inner end of the stem 27 supporting a heat shield 29. Anode 10 is supported on three insulated conductors 30, angularly disposed at 120° and passing through glass-to-metal seals 31.

The annular anode, which is maintained at a positive potential with respect to the cathode to induce an initially radial flow of electrons therefrom, is shown at 16. It is insulatingly supported upon bushing 32 led through the cover plate 21 and insulated therefrom by a glass-to-metal seal 33, and two other similar posts angularly disposed at 120°, to one of which it is electrically connected.

After the electron beam has traversed the annular interaction space, it is received by a collector electrode 34, insulatingly supported from the cover plate 22 which in the specific example described is of steel.

The magnet poles 34' between which the axial magnetic field is produced to cause the electrons injected into the annular interaction space, are centered on the cover plates 21 and 22 by locating shoulders shown at 35.

Oscillatory energy is withdrawn from the main cavity anode 10 by means of an output coupling lead 36 which extends through an aperture in the wall of the main anode to end in a coupling loop of the usual type located within one of the anode cavities. The cavities may be coupled together by the customary strapping.

Assuming that the magnetron is subjected in the normal manner to an axial magnetic field, the electron beam, as well as being projected axially by the electric field provided by the annular deflecting electrode, is also influenced by a continuous circumferential component of force, tending to rotate the electrons in the beam in a circular orbit about the axis of the device.

Under the influence of the electric and the magnetic fields, the electrons enter the annular interaction space projected on spiral orbits, and as electrons are emitted by the whole cylindrical surface of the cathode, there is a cylindrical wall of electrons entering the interaction space all set on a helical course.

It will be understood that after the electrons enter the interaction space they are influenced also by the high frequency wave, and generate or amplify oscillations in the resonant circuit according to well-known magnetron principles.

In a typical arrangement the potentials applied to the electrodes would be as follows

Main anode 10	kv	+ 15
First anode 16	kv	+ 1.4
Post electrode 11	kv	- 1.3
Cathode 12		0
Deflecting electrode 17	kv	- 5
Magnetic field	gauss	570

The main anode has an internal diameter of 2.65" and a length 1.45" and the post electrode external diameter is 1.68". The power output is 5 kw. for a wavelength of 10 cm.

Whilst in the above description the main anode is referred to as containing resonant cavities, it is clear that a segmental type of construction may be adopted for the main anode and that in speaking of resonant cavities it is desired to include such a construction within this term.

What I claim is:

1. An injection type magnetron comprising an evacuated chamber containing a cathode providing an annular electron emissive surface, a first anode of annular shape

surrounding said cathode, a main anode coaxial with said cathode and formed to provide resonant cavities in which oscillations are adapted to be produced, a post electrode coaxial with said cathode and said main anode and forming with said main anode an annular interaction space into which an annular electron beam from said cathode is adapted to be injected, said annular interaction space being axially displaced from said cathode, an annular electrode disposed on the opposite side of said cathode from said interaction space and adapted to deflect electrons initially emitted from said cathode towards said first anode in an axial direction towards said interaction space, and means for producing a magnetic field axially of said cathode and said main anode whereby to impart to the electrons in said beam as they enter said interaction space an angular velocity synchronous with waves propagated in said anode.

2. An injection type magnetron comprising an evacuated chamber containing a cathode providing an annular electron emissive surface, heating means for said cathode, a first anode of annular shape surrounding said cathode, a main anode coaxial with said cathode and formed to provide resonant cavities in which oscillations are adapted to be produced, a post electrode coaxial with said cathode and said main anode and forming with said main anode an annular interaction space into which an annular electron beam from said cathode is adapted to be injected, said annular interaction space being axially displaced from said cathode, an annular electrode substantially enclosing said heating means disposed on the opposite side of said cathode from said interaction space and adapted to be charged negatively with respect to said cathode whereby to deflect electrons initially emitted from said cathode towards said first anode in an axial direction towards said interaction space, and means for producing a magnetic field axially of said cathode and main anode whereby to impart to the electrons in said beam as they enter said interaction space an angular velocity synchronous with waves propagated in said anode cavities.

3. An injection type magnetron comprising an evacuated chamber containing a cathode providing an annular electron emissive surface, means for heating said cathode, a first anode of annular shape surrounding said cathode, a main anode coaxial with said cathode and formed to provide resonant cavities in which oscillations are adapted to be produced, a post electrode coaxial with said cathode and said main anode and forming said main anode an annular interaction space into which an annular electron beam from said cathode is adapted to be injected, said annular interaction space being axially displaced from said cathode, an annular electrode disposed on the opposite side of said cathode from said interaction space and adapted to be charged negatively with respect to said cathode whereby to deflect electrons initially emitted from said cathode towards said first anode in a radial direction towards said interaction space, said annular electrode being constructed to form a heat shielding enclosure around said cathode heating means, means for producing a magnetic field axially of said cathode and main anode whereby to impart to the electrons in said beam as they enter said interaction space an angular velocity synchronous with waves propagated in said anode cavities, and electrode means for receiving electrons from said annular interaction space after they have completed their passage therethrough.

4. An injection type magnetron comprising an evacuated chamber containing a cathode providing an annular electron emissive surface, heating means for said cathode, a main anode coaxial with said cathode and formed to provide resonant cavities in which oscillations are adapted to be produced, a post electrode coaxial with said cathode and said main anode and forming with said main anode an annular interaction space into which an annular electron beam from said cathode is adapted to be injected, a

first anode of annular shape surrounding said cathode and co-operating therewith to provide an electron beam initially proceeding in radial paths to said first anode, said first anode extending into said interaction space, an electrode substantially enclosing said heating means and formed to provide an annular rim extending towards said interaction space, said electrode being disposed on the opposite side of said cathode from said interaction space and adapted to be charged negatively with respect to said cathode, whereby to deflect electrons emitted from said cathode towards said first anode in an axial direction towards said interaction space, and means for producing

a magnetic field axially of said cathode and said main anode whereby to impart to the electrons in said beam as they enter said interaction space an angular velocity synchronous with waves propagated in said anode cavities.
